UNITED STATES PATENT OFFICE.

JOHN F. MONTGOMERY, OF COLUMBUS, OHIO, ASSIGNOR TO THE JOHN WILDI EVAPORATED MILK CO., OF COLUMBUS, OHIO, A CORPORATION OF ILLINOIS.

CAN.

1,079,572.

Specification of Letters Patent.

Patented Nov. 25, 1913.

Application filed November 6, 1912. Serial No. 729,855.

To all whom it may concern:

Be it known that I, JOHN F. MONTGOMERY, citizen of the United States, residing at Columbus, in the county of Franklin and 5 State of Ohio, have invented certain new and useful Improvements in Cans; and I do hereby declare the following to be a full, clear, and exact description of the invention, such as will enable others skilled in 10 the art to which it appertains to make and use the same.

My invention consists of certain new and useful improvements in cans, and relates more particularly to that class of cans in 15 which liquid substances are stored, and from which the contents may be poured from time to time as used, until the can is empty.

My invention is more especially adapted to be used as a receptacle for condensed or 20 aerated milk or evaporated cream but it may be used for any other fluid substance.

The cans now most commonly in use for the purposes above mentioned, are designed to have their tops perforated at two places 25 to allow the contents to be poured out, but it is impossible in this construction to pour the contents in a direct line or without causing some of the liquid to flow down the side of the can, causing the can to present 30 an unsightly appearance and to become unsanitary. By my invention as herein set forth, I have remedied this defect, and have provided a can which may be used practically as a pitcher and from which the contents while being poured are guided directly to any desired point, and without spreading over the can and soiling the same.

In the accompanying drawings, Figure 1 is a perspective view of my improved can 40 having the lower part broken away, Fig. 2 is a top plan view of the same. Fig. 3 is a vertical section on line 2-2 of Fig. 2.

1 is the can body which is made of any suitable material and provided with a top 45 2 which is preferably, though not necessarily, made of metal and is stamped or formed in the manner hereinafter described.

The can top has preferably an annular depressed portion 3 which is intersected at two different points by raised ribs 4. These 50 ribs 4 extend from the edge of the can to the inner circle of the annular depressed portion 3. At the inner ends of the ribs 4, adjacent to the inner circle of the depressed portion, are lower depressed portions 5, 5, 55 which are preferably, though not necessarily, annular in shape.

In use the lower depressed portions 5, 5 are punctured and the contents poured from either aperture thus formed, the contents 60 when the can is tipped flowing from the aperture down a groove 6 which is formed by the ribs 4, 4 on either side thereof, the said ribs forming a spout from which the material may be fed evenly and in a direct 65 line without spreading over the outer surface of the can.

While I have illustrated and described my invention in a preferred form, I do not wish to limit myself to that exact construction, as obviously there may be other forms in which the device may be made without departing from the spirit of the said invention.

What I claim and desire to secure by Letters Patent is:-

1. A can, provided with a top adapted to be punctured at a predetermined point at a distance from the edge of the can to permit the outflow of the contents, and guiding 80 means for the contents provided upon the upper surface of said top, said guiding means extending from the point of puncturing to the edge of the can.

2. A can, provided with a top adapted to 85 be punctured at a predetermined point and with raised ribs forming a groove which extends from said point of puncturing to the edge of the can.

3. A can, provided with a top having an 90 annular depressed portion intersected at different points by raised ribs which form grooves, and lower depressed portions at the inner ends of said grooves, said lower

depressed portions being adapted to be punctured and the liquid fed through one of said grooves, which forms a guide.

4. A can provided with a top having an annular depressed portion adapted to be punctured at different points, adjacent to the inner edge of the same, said annular depressed portion being intersected by

raised ribs, which form grooves from said points of puncturing to the edge of the can. 10

In testimony whereof I affix my signature, in the presence of two witnesses,

JOHN F. MONTGOMERY.
